UNITED STATES PATENT OFFICE.

THOMAS D. McCLUSKEY, OF HARVEY, ILLINOIS, ASSIGNOR, BY DIRECT AND MESNE ASSIGNMENTS, OF PART TO JOHN SCHMAEDEKE AND WILLIAM SCHROEDER, OF BLUE ISLAND, ILLINOIS.

GAME-BOARD.

No. 800,282.

Specification of Letters Patent.

Patented Sept. 26, 1905.

Application filed March 2, 1905. Serial No. 248,064.

To all whom it may concern:

Be it known that I, THOMAS D. McCLUSKEY, a citizen of the United States, residing at Harvey, in the county of Cook and State of Illinois, have invented certain new and useful Improvements in Game-Boards, of which the following is a specification.

One of the objects of this invention is the production of an improved game-board the arrangement of which offers facilities for playing a large number of different games.

The invention further refers to an elastic margin for game-boards which is susceptible of being drawn aside to clear the board, and thus facilitate the playing of the game.

The invention also refers to the various other improvements hereinafter set forth.

In the accompanying drawings, Figure 1 is a perspective view of a game-board embodying the features of my invention. Fig. 2 is a bottom plan view of said game-board. Fig. 3 is a vertical central section through the board. Fig. 4 is a detail sectional view through one of the pockets of the board.

In the construction of a game-board embodying the features of this invention I provide a board 1, preferably rectangular (in this instance square) in outline, and upon its upper and lower surfaces I lay out suitable designs for playing the desired games. The corners of the board 1 are cut away, as at 2, to give access to the pockets 3, which pockets in this instance are formed from metal and are secured to the board 1 at the side edges 35 and bottom of said pockets by means of tacks 4 and screws 5, respectively. At the corners of the pockets and near the adjacent edge of the board 1 are set pins 6, and over these pins and extending along the edges of the board 40 are stretched endless bands 7 of rubber or other suitable elastic material.

The under or reverse side of the board 1 is provided with a central pivotal stud 8, having a base-flange 9, by means of which said stud 45 is fixed upon said board. This pivotal stud 8 is adapted to enter a socket 10 in a base 11 of suitable form to support the board and permit it to turn upon said stud 8.

An arrow 12, having an opening 13 midway 50 of its length, may be mounted on the stud 8 when the board 1 is inverted and certain games played upon the reverse side of the board by

means of said arrow, the base 11 being removed. Such games as pool, caroms, &c., are played upon the upper face of the board, 55 the pivot 8 being provided to permit the board to be turned to present the "shots" to the players in the most favorable and convenient position, and thus to save said players from moving in or leaving their seats. 60 To facilitate shooting a carom that has come to rest against one of the marginal bands 7, said band is stretched outward and downward by the player withdrawing it temporarily from its normal position. When the shot has 65 been made, the band is released, and by reason of its elasticity it immediately resumes its usual position. The elasticity of the marginal bands makes the more skilful or "billiard" shots possible, and thus adds greatly 70 to the interest of the game. By forming the marginal bands in sections—that is, to say, providing one for each side of the board—they are the more easily kept taut and are readily replaced when worn or broken. 75

While I have described the various parts of this board with some particularity, it is clear that there may be a considerable variation from the precise constructions shown without departing from the spirit and scope 80 of the invention. Wherefore I desire to have it understood that I do not wish to limit myself to the exact details herein set forth.

I claim as my invention—

1. A game-board provided with pockets, 85 two supports located on each side of said board near said pockets, a separate elastic cushion for each of the edges of said game-board, which cushion comprises an endless elastic band removably mounted upon said supports, whereby 90 by the said cushions may be freely flexed outwardly from said board.

2. A substantially rectangular game-board, having pockets fixed to the corners thereof, two supports located on each side of said board 95 near said pockets, a separate elastic cushion for each of the edges of said board, said cushion being mounted upon said supports, whereby the said cushions may be freely flexed outwardly from said board.

THOMAS D. McCLUSKEY.
